COMPARTMENTATION MEANS FOR BOWLING BALL BAG

Edwin L. Wilson, Syracuse, N.Y., assignor to Wilson-Ranger Industries, Inc., Syracuse, N.Y., a corporation of New York

Filed Feb. 21, 1961, Ser. No. 90,742
2 Claims. (Cl. 150—52)

This invention relates to a carrying bag for a bowling ball and bowling accessories, and more particularly to a removable tray for dividing the bag into separate compartments for ball and accessories.

Bowling ball bags have heretofore been provided with separate compartments for ball and bowling shoes and other accessories to keep the accessories free from alley wax and stain which may be on the ball, and the ball free from dirt and grit which may be on the shoes and are harmful to the ball. Such compartmented bags have been bulky, expensive to make, or require the heavier ball to be carried on top of the lighter accessories.

It is an object of the present invention to provide a compartmented bag which may be easily and inexpensively made for carrying a bowling ball in a lower compartment and accessories in a separate compartment thereabove.

Another object is to provide such a ball carrying bag with a removable compartmenting means so that the bag may be more easily used for other purposes and so that said means may be used with another replacement bag.

Still further objects are to provide a bag which may be made of light and inexpensive materials, in which the compartmenting means will add structural strength to the bag, which will more readily stand erect, and which will therefore be longer lived.

Other objects and advantages will become apparent from the following description taken in conjunction with the accompanying drawing, in which:

FIGURE 1 is a perspective view of the bag of the present invention;

FIGURE 2 is a sectional view thereof on line 2—2 of FIGURE 1 showing a ball and shoes therein;

FIGURE 3 is a sectional view taken on the line 3—3 of FIGURE 2, a portion only of the shelf being shown in section;

FIGURE 4 is a top plan view of the shelf; and

FIGURE 5 is an end elevation thereof.

In the drawings, a bag 10, preferably made of canvas and reinforced with leather, or of other light and comparatively inexpensive material, has a bottom portion 11, front and rear sides 12 and 13, and end walls 14. Carrying handles 15 are attached to the front and rear walls in the usual manner and a fastening means or "zipper" 16 is provided at the top of the front and rear sides so that they may be closed to form a top portion 18.

The bottom 11 has the usual stiffening lining and a rigid plate 19 is secured thereto by rivets or otherwise for distributing the weight of the ball 20 over the whole of the bottom 11. A ball support 21 is secured to the plate 19 for providing a concave resting surface for the ball.

The bag 10 is preferably of a width equal to the diameter of the ball and of a length substantially longer, although, obviously, it may be any convenient size larger than the ball. In height, the bag substantially exceeds the diameter of the ball and a shelf 23, substantially the same length and width as the interior of the bag, is provided for separating the portion 24 above the ball from the portion 25 in which the ball lies.

Shelf 23 is preferably made of moulded plastic material and is provided with suitable reinforcing flanges and

2

ribs 26. At the center of the shelf a pendant spindle 27 is provided, moulded integrally with the shelf or otherwise rigidly secured thereto.

The spindle 27 is of such size and length that it may be inserted in one of the finger-holes 28 of the ball 20 so that the shelf is supported by the ball and provides a platform for accessories.

In operation the ball 20 is first inserted in the open bag 10, on its support 21. Since the ball is normally carried by the appropriate fingers of the hand inserted in the finger-holes 28, the finger-holes are always at the top of the ball, and it is an easy matter to place the ball on its support with one of the finger-holes centered at the top facing vertically upwards.

Shelf 23 is then placed in the bag with spindle 27 in the centered finger-hole 28. Shoes and other accessories may then be placed on the shelf and the bag closed.

Shelf 23 thus provides compartmenting means for separating the ball in compartment 25 and shoes 30 and other accessories in compartment 24, and keeps the accessories from being crushed by the ball. The shelf, being substantially the same size as the interior of the bag, helps to keep the ball centered in its support 21 and also provides reinforcing means for the side and end walls 12—14 for holding the bag in shape when lifted by the handles 15. In addition, the shelf helps the light weight side and end walls stand erect when the bag rests on the floor.

As will be apparent to those familiar with the art, the invention may be embodied in other specific forms without departing from the spirit or essential characteristics thereof. The embodiment disclosed is therefore to be considered in all respects as illustrative rather than restrictive, the scope of the invention being indicated by the appended claims.

35 What is claimed is:

1. In a bowling ball and accessories bag of substantially greater height than a bowling ball, the improvement comprising a removable tray having length and width dimensions substantially equal to those of the bag, and having a pendant spindle rigidly secured to the center thereof for insertion in the finger-hole of a ball in said bag, thereby supporting said tray on said ball for providing a separate compartment in said bag above said ball.

2. A bowling ball and accessories bag comprising a relatively stiff bottom portion and substantially self-sustaining end, front, and rear walls, said front and rear walls being provided at the top with closure means for forming the top portion of said bag, carrying handles secured to said front and rear walls, a ball support secured to said bottom portion, and a removable shelf member substantially coextensive in length and breadth with the interior of said bag, said shelf member having a pendant spindle element centrally and rigidly secured thereto, said spindle element being dimensioned to be received in the finger-hole of a ball in said bag, whereby said shelf member is supported by said ball for dividing said bag into a lower ball-carrying compartment and an upper accessories-carrying compartment, and said end, front, and rear walls are provided with inward support by said shelf member.
